UNITED STATES PATENT OFFICE.

CLYDE E. TRAVIS, OF FAIRMONT, WEST VIRGINIA.

MAIL-BOX.

1,256,080.

Specification of Letters Patent. Patented Feb. 12, 1918.

Application filed April 18, 1917. Serial No. 162,938.

To all whom it may concern:

Be it known that I, CLYDE E. TRAVIS, a citizen of the United States, residing at Fairmont, in the county of Marion, State of West Virginia, have invented certain new and useful Improvements in Mail-Boxes; and I do hereby declare the following to be a full, clear, and exact description of the invention, such as will enable others skilled in the art to which it appertains to make and use the same.

This invention relates to mail boxes, it has particular reference to private mail boxes which combine the functions of delivery and collection receptacles.

The object of the invention is to provide a combination collection and delivery mail box, which, while being located so as to be exteriorly accessible to the mail man for the collection and the delivery of the mail, is also arranged to deliver the incoming mail into the house and to permit the insertion of outgoing mail into the box from the interior of the house. A further object of the invention, along the lines above pointed out, is to provide a single compartment box in conjunction with which superimposed chutes are arranged to act, alternately as delivery chute and means for depositing outgoing mail.

Furthermore, it is the object of the present invention to combine with a private mail box an alarm mechanism which is operative to be sounded both when mail is delivered into the box and collected therefrom. With the above objects in view, and such others as may hereinafter appear as relating to the details of construction, my invention will now be fully set forth and described, reference being had to the accompanying drawings.

In the drawings:—

Figure 1 is a front elevation of the box with the front removed,

Fig. 2 is a section through the wall of a house having the box mounted thereon,

Fig. 3 is a vertical section through the box.

Fig. 4 is a section on line 4—4 of Fig. 1.

Referring more particularly to the drawings, 1 represents the box or receptacle which has embodied therein the several features of my invention, and, in furtherance of the principal object, is mounted upon the outside of the house wall *a*, transverse slots *b* and *c* cut through the wall *a* registering with corresponding slots cut into the back

of the box 1 at 2 and 3. As best shown in Fig. 3, the slots 2 and 3 are provided, respectively, with the chutes 4 and 5. The chute 4, following the direction of the slots *b* and 2, 60 inclines downwardly into the receptacle 1 so as to slide any mail matter placed upon the inner end thereof within the house forwardly into the receptacle. The chute 4 enters the receptacle at the upper end of the 65 latter and terminates just within the back thereof, so that letters dropping from the end of the chute will have a clear fall to the bottom of the receptacle, whence they may be removed through the door-way 6 in the 70 side of the box.

The chute 5 inclines in the opposite direction to the chute 4, and has its inner end extended into the box and terminated just short of the inner-section of the plane of the 75 chute 5 with that of the chute 4, so that the body of the chute 5 will not interfere with the fall of letters from the end of the chute 4. Hinged to the inner extremity of the chute 5 is a leaf 7, which is normally 80 dropped into the position shown in Fig. 3, the leaf falling of its own weight, and hanging below the end of the chute 5 so as not to interfere with the clearance from the end of the chute 4.

The top of the box 1 is closed by a cover 8 which is hinged to the rear end of the box and inclines downwardly in a usual manner. Connected to the inside of the cover 8 is a flexible element 9 whose opposite end is secured to one free corner of the leaf 7, so that whenever the cover 8 is lifted, the hinged leaf will also be lifted and carried into the plane of the deflector or chute 5. Obviously, in order to permit the leaf 7 to 95 be carried past the front of the box in a horizontal position, it must fall short of the front in its extended position, and in order to close this open space and also to provide a stop to the upward movement of the leaf, a 100 stop ledge or flange 10 is secured to the front wall of the box and projects therefrom into the path of movement of the leaf 7, so that the latter will strike therebelow in its upward movement.

In order to provide a warning and signal to the occupants of the house of the opening of the mail box either for the deposit or collection of mail, I provide an audible signal mechanism which may be arranged to sound 110 at any point within the house, or may be mechanically sounded within the receptacle

1. In the present embodiment I have disclosed the bell 11 mounted upon the rear wall of the receptacle upon a common base with the clapper mechanism 12. This mechanism consists of a casing within which is journaled a disk 13 which carries adjacent its periphery a plurality of arms 14. The free end of the arms 14 carry the clappers 15 which, as the disk 13 is rotated, and the arms 10 14 are extended through centrifugal action successively strike the bell so that the latter is sounded with rapidly intermittent taps. The outer end of the shaft supporting the disk 13 is provided with a drum 16 having 15 a grooved friction surface around which is turned a cable 17. One end of the cable 17 is connected to a tensioned spring 18 secured to the wall of the receptacle, and the opposite end of the cable is connected to the inner face of the door 6, the bight of the cable having been first carried around a grooved pulley 19 so as to properly direction the cable. Connected to an intermediate point of the cable 17 is a branch cable 20, which is 20 also carried over the pulley 19 and then has its free end connected to the lower extremity of a rod or link 21 which is suspended in pivotal relations from the inner face of the cover 8, so that as the latter is raised by the 25 mail man, the cable 20 and through this the cable 17 will be drawn to rotate drum 16. This action will obviously tension the spring 18, so that as soon as the cover 8 is released the cable will be withdrawn to rotate the 30 drum 16 in the opposite direction, so that the bell will be sounded both as the cover is raised and lowered. It should be noted at 35 this point that the spring 18, through the cables and rod 21 will serve to draw the cover 8 to its closed position. In like manner, when the door 6 is opened it draws the cable 17 directly against the tension of the 40 spring 18 and rotates the drum 16 to sound the bell as previously described. A stop to 45 the opening of the door 6 is provided by the toggle links 22, which are connected in proper relation to the inner surface of the door 6 and the wall of the box 1, and a rotatable knob 23 upon the free end of the door 6 50 is provided, the inner end of the stem of the knob carrying a radially projected finger 24 which may be turned into engagement with the inner face of the end wall of the box to lock the door in its closed position. 55 From the foregoing description which discloses the preferred embodiment of my invention, it will be apparent that I have provided a simple and practical arrangement for the most convenient collection and 60 delivery of mail, both from the view point of the mail man and the recipients of the mail. By arranging the compactly constructed receptacle with oppositely directed chutes in

the manner described, I have provided for the delivery of mail into the house and the 65 collection of mail from the box which had been deposited therein from within the house, all with a minimum of mechanism and use of space. The alarm mechanism is so arranged that an audible signal is given 70 when either of the openings into the box is actuated, so that anyone within the house may be forewarned either of the presence 75 of the mail man or of an unauthorized intruder.

What I claim as my invention is:

1. The combination with a wall having a pair of spaced lateral slots formed therein, of a receptacle having slots registering with the first mentioned slots, a downwardly inclined chute extended through the upper one of the slots into the top of the receptacle, an oppositely inclined chute entered through the other side into the receptacle below the first mentioned chute, and means for extending the lower chute beyond the first mentioned chute to permit the passage of mail from the box into the house.

2. The combination with a mail box, of a downwardly inclined chute entered into the 90 upper portion of the box through its rear wall, a second chute entered into the box below the first mentioned chute and inclined in the opposite direction, the first mentioned chute extending into the box so that an extension of its plane over-laps the extremity of the second chute, and an extension for the second chute adapted to cause it to intersect said plane.

3. The combination with the mail box of a 100 downwardly inclined chute entered into the upper portion of the box through its rear wall, a second chute entered into the box below the first mentioned chute and inclined in the opposite direction the first mentioned 105 chute extending into the box so that an extension of its plane overlaps the extremity of the second chute, and a leaf hinged to the second chute for the purpose of extending it across the plane of the first chute.

4. The combination with a mail box of a downwardly inclined chute entered into the upper portion of the box through its rear wall, a second chute entered into the box below the first mentioned chute and inclined 115 in the opposite direction the first mentioned chute extending into the box so that an extension of its plane overlaps the extremity of the second chute, a leaf hinged to the second chute for the purpose of extending it 120 across the plane of the first chute, a closure for the box, and means for lifting the leaf into extended relation when the closure is opened.

In testimony whereof, I affix my signature. 125
CLYDE E. TRAVIS.
